William Rehe Inventor

By Frank Kipper Attorney

UNITED STATES PATENT OFFICE.

WILLIAM REHE, OF ROCHESTER, NEW YORK.

WILLOW-CHAIR CONSTRUCTION.

1,412,197.

Specification of Letters Patent. Patented Apr. 11, 1922.

Application filed April 29, 1921. Serial No. 465,558.

To all whom it may concern:

Be it known that I, WILLIAM REHE, a citizen of the Republic of Germany, residing at Rochester, in the county of Monroe and 5 State of New York, have invented certain new and useful Improvements in Willow-Chair Constructions, of which the following is a specification.

The object of this invention is to construct 10 a chair made up of willow members in a new and improved manner.

This and other objects of this invention will be fully illustrated in the drawings, described in the specification and pointed out 15 in the claims at the end thereof.

In the accompanying drawing:

Fig. 1 is a perspective skeleton view of the chair.

Fig. 2 is a sectional view of a portion of 20 the seat, the section being taken on the line $2x-2x$ of Fig. 1.

In the several figures of the drawing, like reference numerals indicate like parts.

Heretofore chairs have been woven by the 25 use of willow, reed, rush and other flexible materials. Of these the willow stems are the stiffer and heavier and the reed stems are the lighter and more flexible. Heretofore the reed chairs have been made with a 30 wooden frame work to make them more stiff and rigid. Because of the small size and flexibility reeds could be woven around the members of the wooden frame successfully while it has not been deemed practical to 35 weave or bend willow around the members of such a frame. Because of this, the willow chairs have been found lacking in strength and stiffness given to the reed chairs by the wooden frame.

40 I have now found a way to make a willow chair in which a wooden frame is used in which the willow is woven over and around the wooden frame work, thus preserving all the finish or the ornamental appearance of 45 the willow chair and making it even stronger and more rigid than the reed chair.

The willow chair which is illustrated in the accompanying drawing, is provided with wooden reinforcing frame 1 similar to the 50 frame heretofore used in making reed chairs. This frame comprises the seat member 2 which is built up of the front member 3 and the back member 5 with the side members 6 and 7 linking them together. The seat 2 is 55 supported on four legs 8, 9, 10 and 11. These legs are fastened to the corners of the seat

by means of nails near the upper end thereof and are braced on the seat by means of the braces 12, 13, 14 and 15 near the lower end thereof. The braces 12 to 15, inclusive, are 60 willow members and are adapted to project into the angular holes 16 provided in the seat 2. These holes are drilled in the seat at an angle to top and bottom thereof, with the incline toward the middle of the side or 65 end of the seat. The willow members comprising the braces, are bent at the upper end to project into the holes 16. An angular brace is thus formed which takes up any side thrust on the legs of the frame and holds 70 the legs rigidly in place on the seat without the aid of nails or other fastening means ordinarily used to fasten the braces to the seat. The lower end of the braces are fastened to the legs by means of nails that are 75 driven through the brace into the legs. The braces, however, are not fastened to the legs at their lower end until the willow work is practically completed. In this lies the secret which enables the making of a willow chair 80 with a wooden frame. The braces that are being used in reed chairs, are permanently fastened at the top and bottom when the wooden frame is being made. This is possible because the reed members are pliable 85 and can be woven around the braces. It is impossible, however, to do this with willow members, some of which are as much as one-half inch in diameter and comparatively stiff even when wet, in which state the willow 90 is being worked.

When the willow members have been woven around the legs of the frame down to the point where the lower ends of the braces are to be attached, the braces are nailed to 95 the legs and the willows are then wound over the outside of the legs and braces to conceal the joints between the braces and the legs. In this way, the wooden frame can be properly braced and reinforced without interfering 100 with the placing of the willow thereon and without changing the appearance of the finished chair and the chair can be made with a wooden frame to add to its supporting strength which has heretofore been possible 105 only with reed chairs or other equally pliable material.

Willow chairs which have heretofore been made, have not found the market and sale of reed chairs, in spite of the fact that 110 the finish of a willow chair presents a better appearance than a reed chair. This is solely

due to the fact that the strength of the willow chairs has been way below that of the reed chair. With the aid of the frame work above described, the willow chair can now be made the equal in strength of the reed chair.

I claim:

1. A chair, comprising a frame, a seat formed by said frame, legs supporting said frame, willow members woven around said seat to form the sides and back of said chair, willow members wound around said legs below said seat, angular braces between said seat and said legs, said angular braces being loosely fastened to said seat and being rigidly fastened to said legs.
2. A chair, comprising a frame, having a seat formed thereby, legs supporting said

seat at the front and back thereof, willow members ornamenteally woven around said seat and said legs above and below said seat, said seat having angular holes therein inclined toward the middle of the front, back and sides of said seat, braces having an angular extension formed at one end thereof, 20 said angular extension extending into said angular holes and forming a shoulder on the upper end of said braces to hold said braces in place on said seat, means to fasten the lower end of said braces to said legs, said 25 braces being fastened to said legs after the ornamenteally woven willow members are woven around said seat and said legs.

In testimony whereof I affix my signature.

WILLIAM REHE.
